UNITED STATES PATENT OFFICE.

JOHN P. SCHENKL, OF WORCESTER, ASSIGNOR TO HIMSELF AND E. A. DANA, OF BOSTON, MASSACHUSETTS.

IMPROVEMENT IN THE CHAMBER OF ORDNANCE AND OTHER FIRE-ARMS.

Specification forming part of Letters Patent No. 23,746, dated April 19, 1859

To all whom it may concern:

Be it known that I, JOHN P. SCHENKL, of Worcester, in the county of Worcester and State of Massachusetts, have made a new and useful Invention relating to Fire-Arms and Ordnance; and I do hereby declare that the same is fully described and represented in the following specification and the accompanying drawing, which exhibits a longitudinal section of a cannon or piece of ordnance with my invention applied thereto, such invention being, properly speaking, an improvement in the application to a piece of ordnance of a secondary or smaller barrel for the purpose of containing a separate charge of powder, whose explosion, preparatory to that of the main charge, is to operate so as to overcome the *vis inertiae* of the projectile or charge of shot, and thereby diminish the recoil of the gun.

On the 12th day of October, A. D. 1858, Letters Patent of the United States of America were granted to myself and Edward A. Dana for the invention on which the present may be said to be an improvement.

The nature of the said present improvement consists in the combination of an intercepting rod or leader with the hollow tube or auxiliary charge-chamber, and a projectile suitably adapted to the gun or piece of ordnance. Such rod or leader may be made of wood or any other suitable material, and is to be so constructed and arranged that while one end of it shall connect with and support, by entering or otherwise, the projectile, sabot, or wad, the other end may be fitted to enter for a certain distance the interior walls of the secondary barrel aforesaid, leaving, however, a sufficient space therein beyond for the initial powder-charge. The space in the main barrel of the piece immediately surrounding the rod or leader can in this way be used as well as that which surrounds the secondary barrel for holding the main powder-charge, thus enabling me by simply increasing the length of the said rod or leader to reduce in the same proportion the length of the projecting portion of the secondary barrel, even to the extent of dispensing with all projection of the latter, in which case the secondary barrel aforesaid would be simply a

smaller chamber formed in the bottom or breech of the piece. The construction, however, which I prefer as most conducive to economy of space and durability is to have so much of the secondary barrel as is to contain the initial powder-charge formed or placed in the bottom or breech of the piece, while the rest of it may project therefrom into the main barrel of the piece, the same as is shown in the drawings; also, in making the entering portion of said rod or leader and the interior walls of the secondary barrel both slightly conical or tapering, so that the former may easily enter and closely fit and be stopped by the latter; also, in forming or fixing in or on the entering portion of said rod or leader a ring or cup of some elastic or ductile material, which, by the explosion of the initial powder-charge, shall be expanded closely against the walls of the secondary barrel as the rod or leader is driven therefrom, and thus prevent the premature explosion of the main powder-charge; also, in forming said secondary barrel of a sufficient depth to contain both the initial powder-charge and the entering portion of the rod or leader, the vent-hole of the piece to be carried down and open directly into the aforesaid initial powder space.

In the drawing the figure represents a gun or piece of ordnance, of which B is the bore, b b, in connection with a, is the secondary barrel, C the vent-hole, a the initial powder-charge space, g g the main powder-charge space, p the rod or leader, e the ring or cup in or on the same, s a sabot connected with and supported by the rod or leader p, and S a shot or shell, the operation of all which, when the piece is loaded and fired, is as follows: The initial charge in space a being first ignited by the vent-fire, and exploding, imparts motion to the rod p, sabot s, and projectile S, which is instantaneously followed by the explosion of the main powder-charge in space g g, fired by the flame following the rod or leader p, by which process the *vis inertiae* of the projectile has been overcome before the explosion of the main charge takes place, thus greatly diminishing the recoil and strain on the gun as compared with the ordinary mode of loading and firing.

The advantage of this improvement is that

enables me to make the secondary barrel of less length where it projects into the main barrel, thus more effectually securing it against injury.

Having thus described my invention, what I disclaim and claim is as follows:

I do not claim the invention claimed and described in the United States Patent numbered 21,802; but I do claim the combination

of an intercepting rod or leader, *p*, with the secondary barrel or auxiliary charge-chamber, and a projectile suitably adapted to the gun or piece of ordnance.

JOHN P. SCHENKL.
